UNITED STATES PATENT OFFICE.

CUTHBERT BURNETT, OF GRANGE, NEAR DURHAM, ENGLAND.

APPARATUS FOR WASHING COAL, COKE, &c.

SPECIFICATION forming part of Letters Patent No. 700,735, dated May 27, 1902.

Application filed April 18, 1901. Serial No. 56,432. (No model.)

To all whom it may concern:

Be it known that I, CUTHBERT BURNETT, engineer, a subject of the King of Great Britain, residing at Grange, near Durham, in the county of Durham, England, have invented new and useful Improvements in Apparatus for Washing Coal, Coke, or other Minerals, Specially Applicable for Treating "Slack" or Small Coal for Coking, of which the following is a specification.

In coal-washing apparatus in which the dirt or heavy particles are discharged at the higher end of a washing-trough—such, for instance, as a fixed trough with an endless belt provided with scrapers, said belt moving in a slanting upward direction or a trough-shaped endless belt provided with dams and also moving in a slanting upward direction—it has been found that there is a tendency for the washed coal to contain a notable proportion of pyrites or other heavy impurities and also that the washing-water while being circulated in the washing apparatus contains in suspension a considerable proportion of fine pyrites or other heavy impurities, or that special means, such as a sand-recovery trough, is sometimes employed for removing the said impurities. A further difficulty, more especially met with in washing what is called "slack" or fine coal, is that the effluent water still contains in suspension a material proportion of fine coal, so that the well soon becomes silted up therewith unless a settling tank or pond is provided with or without special means for removing or elevating the silt.

Now the object of my invention is to secure perfect washing of the coal in a simple and efficient manner and by the employment of a simple and easily-controlled automatically-acting plant.

Figures 1 and 1^a together show in side elevation, partly in section, a coal-washing apparatus embodying my invention, the rakes for raking and spreading the coal to be washed being omitted for the sake of clearness. Fig. 2 is a section of the upper web of the endless washing-belt and the trough wherein it works; and Fig. 3, a longitudinal section through part of said upper web. Figs. 4 and 4^a together show in side elevation, partly in section, a coal-washing apparatus embodying modifications, and in said views I have shown the lo-

cation of the rakes. Fig. 5 is a cross-section of the upper web of belt and the trough wherein it works; and Fig. 6, a longitudinal section through part of the upper web. Fig. 7 is a detail view of bottom and of the washed-coal elevator. Fig. 8 shows a preferred form of slurry-elevator, and Fig. 9 is a cross-section of same on a larger scale. Fig. 10 is a detail side view of the automatic rakes and gear for driving the same and the coal-chute slide; Fig. 11, a vertical cross-section on line 1 1, Fig. 10; Fig. 12, a vertical cross-section on line 2 2, Fig. 10; and Fig. 13, a vertical cross-section on line 3 3, Fig. 10.

Referring now to Figs. 1, 2, and 3, the endless washing belt or band A of known or suitable construction and with the upward slope toward the delivery end for the pyrites or other heavy impurities while the other end is used for the delivery of the washed coal is according to my invention at or near that end formed with a dip, as at A', or the belt may have more than one such dip at or near that end. In Fig. 1^a the dip is, as an example, shown quite near that end and the end slope somewhat steeper than at the opposite end of the belt. The belt A, mounted on hexagon pulleys and actuated in the usual manner, is moved continuously in a trough G (shown to a larger scale in Figs. 2 and 3) toward the other or higher end, from right to left in Fig. 1, as indicated by the arrow. The belt is near that higher end supplied with coal to be washed from a hopper B in quantities regulated by a slide B', link B², and regulating hand-lever B³.

N is an elevator for supplying the hopper with coal. The washing-water is supplied from a tank C partly by a pipe C', regulating-cock C², nozzle C³, and small trough or feed plates C⁴ and partly by a pipe C⁵, regulating-cock C⁶, and nozzle C⁷. The water thus supplied washes the coal and floats it down to the aforesaid dip at A', where the water will be comparatively at rest, so that a considerable proportion of the fine coal previously held in suspension will deposit in the said dip, and as this takes place constantly, while the large coal also accumulates there, a perfect admixture of the small and the large coal takes place in the dip. This washed coal is removed from the dip preferably by

- an elevator D, with perforated buckets for draining off the water, or by any other suitable lifting appliance which will allow any little water to drain back into the dip A'. 5 The elevator D conveys the coal to a hopper E or other receptacle or direct into a truck F, as local circumstances may require it. The bulk of the water flows off from the dip A' over a suitable weir, weirs, or strainers— 10 such, for instance, as the gauze-covered overflow-openings h—into a gutter H at each side and thence by pipe H' to a well or cistern I, from whence the sedimentary part of the water containing some fine coal, technically 15 known as "slurry," is raised, by preference, by an elevator K in order to be discharged onto the belt A for being re-washed. The comparatively clear water above the foot of the elevator is raised by a centrifugal pump L 20 or other pump or means for delivery back to the supply-cistern C in order to be circulated again over the washing-belt A. The great advantage of employing an elevator K is that the slurry, which may contain some 25 heavy impurities that have been carried along with the effluent water along with the fine coal, will be raised in order to be further washed. This process of washing the coal in the proper manner is secured by a suitable 30 rate of coal-supply and by a proper adjustment of the lower end of the elevator D in the dip A', so that the latter carries away the maximum quantity of clean washed coal. The means of adjustment are shown 35 in Fig. 1^a and more clearly in the detail view, Fig. 7, where the bearings D² of the bucket-chain spindle are adjustable as to height in quadrants D³ by means of rods D⁴ and screw D⁵ with hand-wheel D⁶, or instead of varying 40 the immersion of the lowermost bucket of the elevator I may vary the speed of the elevator.
- D' is a chute hinged to the bottom of the elevator-case and riding on the belt A for 45 preventing the coal from passing behind the foot of the elevator. The belt A is provided with shallow dams A³ on the upper or outer side for carrying along the heavy impurities and provided with scrapers A² on the under 50 or inner side for removing what little fine stuff may have passed through the joints of the belt and have deposited on the floor of the trough G, or they may be, as shown in Fig. 3, on every other link of the belt A. 55 This deposit is thus continuously carried to the aforesaid well or cistern I, whence it is raised as part of the slurry by the aforesaid elevator K at that place, so that it may be re-washed.
- 60 M' is a dirt-hopper, and M is a dirt-conveyer, which latter, however, is not necessary unless the apparatus is arranged at a low level, as shown in Fig. 1.
- Instead of using a bucket-chain elevator, 65 as K, for raising the slurry I may advantageously employ an elevator of the form shown in Figs. 8 and 9, where dams K' take

the place of the buckets, and these dams are automatically cleaned by the scraper K² on the weighted bell-crank lever K³. The dams 70 K' fit the inside of the elevator pretty closely, as will be seen in Fig. 9, but nevertheless permit the water to drain off.

In connection with the coal-washing apparatus I prefer to use automatic rakes for raking the coal as it is delivered onto the belt A 75 from the hopper B and also for raking the dirt as the latter is carried up to the highest left-hand end of the endless belt A.

I will now describe the construction and 80 arrangement of the coal-raking appliances, referring more particularly to Figs. 4, 4^a, 5, and 6, and to Figs. 10, 11, and 13.

In the apparatus, Figs. 4, 4^a, 5, and 6, is shown an endless belt A, mounted on two 85 chains A^x and having upright sides A⁴, which, as seen in Fig. 6, are in parts overlapping each other in order that the belt may take a curved direction when passing over the hexagon end pulleys and when passing the depressed part 90 of the flow of the trough G at the place of the dip A'. In this case I have shown two wells I and N, both near the washed-coal-delivery end. This end is sufficiently low to allow the water to pass over the end of the belt and 95 thence through a spout from the trough G into the well I, where the slurry will settle somewhat and is raised by the elevator K and thence discharged onto the belt A to be again washed and finally to be discharged into the 100 coal-hopper E by the elevator D, as in Fig. 1. The well I has, however, an overflow-passage I' for the comparatively clean water to a well N. The water in the latter is by a centrifugal pump L or other pump and by the 105 pipe L' conveyed to the water-tank C. In this arrangement the apparatus is elevated sufficiently high to dispense with the dirt-conveyer M, that was shown in Fig. 1, and the dirt is delivered direct into the dirt-hopper 110 M' and thence into the truck. O is the overflow-pipe from the water-tank C to the pump-well M. P is a pit containing coal to be 115 washed, and N^x an elevator for raising the coal to the coal-hopper B. U is a gutter for receiving any water that may overflow from the bottom of the trough G and which by the 120 pipe U' runs into the settling-well I. At the higher left end of the washing-belt A, Figs. 1 and 4, is shown the arrangement of two sets 125 of the automatic rakes referred to, and in Figs. 10 to 13 they are shown more clearly and drawn to a larger scale and in conjunction with means for intermittently opening the gate or slide, whereby coal is admitted to 130 the washing-belt from the dry-coal hopper B. The rakes are disposed in two sets, one set Q to the right of the coal-hopper B and one set Q' between the water-nozzles C³ and C⁷. The rakes Q are mounted on a shaft R, which 135 by a lever R', fixed on a spindle R⁵, and by rod R², jointed to the lever R', receives reciprocating motion in the axial direction from an eccentric R³ on a rotating spindle R⁴. The

other set of rakes Q' are mounted on a shaft S , which receives reciprocating motion in the axial direction by rod S' from a lever S^2 on the aforesaid reciprocated shaft R^5 . By means of the double set of rakes the coal on the belt A is subjected to a very effectual raking or overturning action, which tends to separate the pyrites or other heavy or extraneous materials therefrom, the material being subject at the same time to the powerful action of the water from the nozzles C^3 and C^7 . On the spindle R^5 is fixed a disk T , Fig. 13, provided with a slot-crank or slot T' , to which is adjustably jointed a rod T^2 . This rod is jointed to one end of a double-armed lever T^3 , its other end being connected to a slide B^X at the exit end of the chute from the dry-coal hopper B . This slide thus obtains a reciprocating up-and-down motion and admits coal to the small trough or feed plate C^4 , from whence the coal, aided by the jet from the water-nozzle C^3 , drops onto the washing-belt A .

What I claim as my invention, and desire to secure by Letters Patent, is—

1. In a coal-washing apparatus in which the heavy impurities or dirt are discharged at the higher end of the slope of a sloping endless belt moving toward that end while the washed coal is floated down toward the other end, a dip in said belt near the last-named end for causing the washing-water to be there comparatively at rest, in order that the fine parts of the washed coal held in suspension, may deposit there in combination with means for raising the washed coal from such dip, substantially as set forth.

2. In a coal-washing apparatus in which the dirt or heavy impurities are discharged at the upper end of a sloping endless belt, having motion toward said end, a trough in which said belt travels, means for washing the coal and floating the washed coal down the slope of the belt, a dip in said belt at or near the lower end of its slope, and means for raising the washed coal from said dip, substantially as and for the purpose set forth.

3. In a coal-washing apparatus, the combination of a sloping endless belt, a trough in which said belt has motion toward the higher end of the slope, scrapers on the inner or under side of the belt for scraping said trough, means near the higher end of the slope of the belt for supplying coal and water thereto in regulated quantities, and a receptacle at said higher end of the belt for receiving the impurities, substantially as set forth.

4. In a coal-washing apparatus the combination of a sloping endless belt moving toward the higher end of the slope means near that end for supplying coal and water in regulated quantities to the upper web of the belt, a set of transversely-reciprocated rakes at the coal-supply exit and another set of such rakes between such exit and the water-supply exit substantially as and for the purpose set forth.

5. In a coal-washing apparatus the combination of a sloping endless belt moving toward the higher end of the slope, a dry-coal-supply hopper, near that end with means for regulating the delivery of coal therefrom a feed-plate or trough receiving the coal from the coal-hopper, a water-supply tank nearer that end, a pipe therefrom with regulating-cock and exit-nozzle which discharges washing-water onto the coal in said feed-trough, another pipe from said supply-tank with regulating-cock and exit-nozzle which discharges washing-water onto the belt nearer the water-tank, a set of transversely-reciprocated rakes at the coal-supply exit and another set of such rakes between the two water-supply exits, substantially as and for the purpose set forth.

6. In a coal-washing apparatus the combination of a sloping endless belt moving toward the higher end of the slope, means substantially as described near that end for supplying coal and water in regulated quantities to the upper web of the belt, a dip in the belt at the other end of the belt, a trough at said dip; a settling-well for receiving from the lower end of the slope of the belt the overflow water with matter suspended therein, an elevator for raising the slurry therefrom and delivering it onto the belt for being rewashed, a pump-well receiving the overflow water from the settling-well, a pump to convey the water therein to the water-supply tank, and an overflow-pipe from the latter to the pump-well substantially as set forth.

7. In a coal-washing apparatus, the combination of the sloping endless belt moving toward the higher end of the slope, means for delivering coal to said belt near the said higher end of the slope, means for supplying water to the belt and floating the coal down the slope, an elevator near the bottom of said slope for raising the washed coal from the belt, said elevator having a hinged bottom riding on said belt and a settling-well for receiving from the lower end of the slope the overflow-water and matter held in suspension therein, substantially as and for the purpose set forth.

8. In a coal-washing apparatus, a sloping endless belt having motion toward the higher end of the slope, means for feeding the coal to be washed to said belt at or near said higher end, a dip in the belt near the lower end of the slope causing the wash-water to be there comparatively at rest; in combination with an elevator for raising the washed coal from said dip, and means for adjusting the intake of the elevator relatively to the dip, substantially as and for the purpose set forth.

In testimony whereof I have signed my name to this specification in the presence of two subscribing witnesses.

CUTHBERT BURNETT.
